UNITED STATES PATENT OFFICE

94,524

DESIGN FOR A CUP HOLDER

Walter Dorwin Teague, Forest Hills, N. Y., assignor to Corning Glass Works, Corning, N. Y., a corporation of New York

Application June 18, 1934, Serial No. 52,227

Term of patent 7 years

To all whom it may concern:

Be it known that I, Walter Dorwin Teague, a citizen of the United States, residing at Forest Hills, in the county of Queens, and State of New York, have invented a new, original, and ornamental Design for a Cup Holder, of which the following is a specification, reference being had to the accompanying drawing, forming part thereof.

The figure is a perspective view of a cup holder, showing my new design.

I claim:

The ornamental design for a cup holder, as shown.

WALTER D. TEAGUE.
